UNITED STATES PATENT OFFICE.

EUGENE JAMES SWEENEY, OF ROCKFORD, ILLINOIS.

PLANE.

Application filed July 27, 1922. Serial No. 577,819.

To all whom it may concern:

Be it known that I, EUGENE J. SWEENEY, a citizen of the United States, and a resident of Rockford, in the county of Winnebago and State of Illinois, have invented a new and Improved Plane; of which the following is a full, clear, and exact description.

This invention relates to planes and particularly to an improvement over my Patent No. 1,400,330, and has for an object to provide an improved arrangement for setting the bit.

Another object of the invention is to provide a simple construction wherein the bit may be readily fed forwardly or rearwardly and locked in any of its adjusted positions.

An additional object is to provide a plane with adjusting means which will automatically lock the bit in any adjusted position, the same being associated with a guide to always hold the parts in operative position.

In the accompanying drawing—

Figure 1 is a longitudinal vertical section through a plane disclosing an embodiment of the invention.

Figure 2 is a top plan view of the plane shown in Figure 1.

Figure 3 is a perspective view showing part of the bit adjusting mechanism.

Figure 4 is a perspective view showing a threaded shoulder or abutment embodying certain features of the invention.

Figure 5 is a perspective view of a guiding rod.

Referring to the accompanying drawing by numerals, 1 indicates the stock of a plane which is of a well known construction and identical with that shown in my prior patent above referred to, said stock having side flanges 2 and merging into a frog 3 having a rearwardly extending bearing section 4, the face of which accommodates the bit supporting bed 5 which bed is preferably of wood and held in place in any suitable manner, as for instance, by a screw 6 as well as the ribs 7 fitting into suitable grooves in the bed. A comparatively large aperture 8 is arranged substantially centrally of the bed 5 accommodating the end of pin 9 which

pin is preferably beveled at the lower end and extends through one of the tapering apertures 10 formed in the bit 11.

It will be noted from Figure 1 that the bit 11 is provided with a comparatively large number of apertures 10 arranged in a row

centrally of the bit. In addition to these apertures, a lever 17 is welded, riveted or otherwise rigidly secured to the bit 11 on the upper or outer face and extends a short distance beyond the bed 5 so that it may be easily shifted laterally in order to bring the cutting edge 12 in proper alignment. The lever 17 is provided with a turned down end 18 in order that the parts may be more readily adjusted when it is necessary to properly set the edge of the bit 11. On top of the bit 11 is arranged a shaving breaker 19 extending from near the cutting edge of bit 11 to a point substantially in line with the aperture 8. This shaving breaker may be of any suitable material but is preferably formed of wood and is held in place by a set screw 21 carried by a transverse clamping bar 20 rigidly secured to in any suitable manner or formed integral with the flanges 2.

In order to prevent the shaving breaker 19 from becoming dislocated, suitable screws 14 extend through the bar 20 and into the breaker 19. The flanges 2 are provided with integral extensions 23 which are provided with an integral cross bar 24 having a threaded aperture for receiving the threaded end 25 of the abutment 26, which abutment has a large threaded aperture which is adapted to receive the screw 27, said screw being hollow and carrying a rod 28, said rod having an enlarged end 29 and a threaded end 30, said threaded end being adapted to receive the nut 31 whereby the end 29 is clamped tightly against the screw 27. The end 29 is provided with an enlargement 32 on one side having a threaded aperture 33 for receiving the threaded end 34 of the guide rod 35, which guide rod extends loosely through the ear 36 of the abutment 26 whereby said abutment cannot rotate while permitting the screw 27 to freely operate for moving the enlargement 29 back and forth.

The pin 9 is provided with a threaded portion 37 fitting into one of the threaded apertures in the enlargement 29 so that when the threaded member 27 is rotated, the pin 9 will be moved bodily for adjusting the bit 11. When the bit has been adjusted as far as the threaded member 27 will permit, the pin 9 is withdrawn from one of the apertures 10 and the threaded member and associated parts moved back so that the end of the pin 9 may fit into the next aperture 10.

of the bit 11 in order to produce an additional adjustment.

In operation the plane is used in the usual manner, as for instance, by grasping the knob 38 and the handle 39 for moving the plane back and forth as desired. When it is desired to move the bit downwardly to produce a deeper cut, the screw 27 is adjusted accordingly. In case the cutting edge 10 of the bit is not parallel with the bottom of the plane, lever 17 may be moved readily for shifting the bit to produce a proper alignment of the cutting edge, said bit swinging on the pin 9.

15 What I claim is:—

1. In a plane, a bit having an aperture therein intermediate its ends, a pin extending into the said aperture to clamp in place said bit, a bar having a head provided with an opening at one side supporting said pin, a tubular member threaded at its outer surface and carrying said rod, a support having a threaded opening for said tubular member, said tubular member being movable longitudinally in said support by rotating the same, said support being formed at one side with an ear having an opening and an L-shaped guiding rod having one leg inserted in the opening of the head and the other 25 opening in said ear to prevent rotation of

said rod when said tubular member is rotated.

2. In a plane a bit provided with a series of spaced openings on its longitudinal axis, and means at one end to manually adjust it laterally, a pin having a pointed end adapted to enter any one of said openings according to the position of said bit to clamp the bit in place, means carrying said pin and moving the same longitudinally of the bit 35 to adjust the position of the bit longitudinally, and means associated with said first-mentioned means to prevent a lateral shift of the said pin.

3. In a plane, a bit having an aperture 45 therein intermediate its ends, a pin extending into said aperture, a bar connected with said pin and extending at right angles thereto, a tubular member through which said bar extends, said tubular member being rotatably mounted on the bar and threaded exteriorly, a stationary abutment having threaded apertures for receiving said threaded tubular member whereby when the threaded member is rotated the pin will be 50 moved longitudinally with respect to the bit and a guiding rod for preventing the rotation of said abutment extending between the abutment and the bar.

EUGENE JAMES SWEENEY.
